LAMP

David Trompeter, Sandy Hook, Conn.

Application July 3, 1945, Serial No. 602,986

4 Claims. (Cl. 240—123)

1

The subject of this invention is a new and valuable electric-light lamp-entity.

The fundamental concept of the invention is a make and break device for the circuit which energizes the illuminating means (as one or more incandescent lamp or light bulbs), with such device capacitated to be thrown to circuit making or circuit breaking condition, not as usual at the cost of having to grope and fumble for the difficult to find actuator (such as a pull-chain or push-button or turn-leaf), but as the result merely of slightly tilting the lampshade; the arrangement being such that this tilt may occur as the result of a relatively slight tilt-imparting thrust applied to the lampshade along any one of a multiplicity of directions of thrust application with all such directions differentially angularly displaced circumferentially of the general lamp structure. Thus, the lampshade may be readily manually intercepted in the darkest room, regardless of the direction of approach toward the lamp, and so regardless of what a real or edge subdivision of the lampshade is thus intercepted; and then the lampshade may be given its tilt-imparting thrust at the portion of the lampshade thus intercepted. This is the fundamental principle of the invention; a principle wholly new in the art so far as I am aware. As contradistinguished from the inaccessible pull-chain, push-button or the like, relatively minute as compared to the general expanse of the lamp as a whole, and time-consuming and annoying to locate when it is desired to turn the lamp on or off, particularly the former and therefore generally in a dark room, the present invention offers a manipulable means of considerable expanse and hence immediately interceptible by touch in pitch-black darkness, there is provided by the present invention a manipulable means for turning the lamp on or off which is of considerable expanse and so immediately perceptible in complete darkness, and which, furthermore, is always operable in response to hardly more than the slightest of upward or downward finger-tip thrusts at that one of a multiplicity of possibly engageable points which is at the moment in line with the direction of interceptive approach to the lamp.

The invention will be more fully understood, and the features above mentioned and others, and the various objects and advantages contemplated, from the following description of certain now preferred embodiments as illustratively shown in the accompanying drawings, in which:

Fig. 1 is a fragmentary side elevational view, partly broken away and partly in section, showing

an embodiment having a universally tiltable lampshade pursuant to the invention, as the word tilt has been used herein;

Fig. 2 is a side elevational view, partially broken away, showing a modification.

Referring to the drawings more in detail, and first particularly to Fig. 1, the type of lamp here shown is of the depending bulb design, and comprises a pedestal 15 of any shape fancied by the designer; a superstructure including a pair of bulb sockets 16 for the customary incandescent light bulbs 17 and a cup-shaped canopy or body generally marked 18 from which the sockets 16 depend; a finial 19 for threaded attachment to the top of the body 18; a skeletal lampshade support or frame 20 fashioned in the usual way of a plurality of welded together wire members portions of which latter converge to join a central ring or eye 20a for facilitating dependable securing of said frame to the body 18 by the finial 19; and a gravity-positioned lampshade 21 fitted upon and lying embracingly around the frame 20.

In accordance with accepted lamp manufacturing practice, the body 18 is made up of two spun metal parts; an approximately hemispherical lower part or receptacle 22, and an upper part or cap 23. Also pursuant to accepted practice, the receptacle 22 at its lower end is suitably fixed to the top of the pedestal; which latter, like the body 18, is hollow for the passage therethrough of the current conducting wires going to the appropriate terminals within the sockets 17.

However, unlike the previous methods of lamp manufacture, neither of said wires is interrupted at some point between the top and bottom of the pedestal for interposition of the usual push-button, turn-blade or pull-chain operated switch for opening and closing the lamp circuit therat. On the contrary, the wire for switch interposition therein is still unbroken when both wires beyond the top of the pedestal enter the interior of the body 18 for connection in the familiar way with the sockets 17. The wire to take the switch is broken within the body 18, and the two wire ends which result are connected respectively to the terminals of a switch to be opened and closed according to the invention by relative movement between two parts of the lamp assemblage.

In the embodiment now being described, these lamp parts are the lampshade 21, and with it the frame 20, on the one hand, and the body 18 atop the pedestal 15, on the other.

Said switch, indicated generally at 26, is desira-

bly a toggle switch, and is shown as a toggle switch of standard type. A toggle switch is preferable, because a characteristic thereof is that it incorporates an actuator which when moved a certain distance in an appointed direction throws the switch from open to closed condition if it was previously open, and throws the switch from closed to open condition if it was previously closed. A well-known form of such a switch is one wherein a pull on the actuator reverses the switch, and wherein the snap-over spring-means of the switch restores the actuator to normal partial retraction within the switch incidental to a reversal of its circuit affecting condition. The switch 26 illustratively shown herein is a switch of the kind just above described; the same being manufactured by McGill Manufacturing Co., of New York, N. Y., and commercially purchasable on the open market under the designation Leyolier fixture switch for 3 amp. 250 volts-6 amp. 125 volts. As the construction and details of operation of this switch are well-known, its interior mechanism is not herein illustrated to an extent beyond that required for complete understanding of the present invention; and it will suffice to say here that said switch has its working parts enclosed in a casing 27 and that operatively connected to its interior mechanism is a universal-joint-type mounted actuator 28 projected from the casing for pull through a relatively short distance to effect reversal of the condition of the switch.

The switch casing 27 is suitably fixed in the body 18, as at 29, so that the actuator 28 is vertically uppermost and arranged as shown, that is, to extend through and project somewhat above the top of a short upstanding collar 23a on the cap 23. The thus projected upper end portion of the actuator, which is cylindrical in form, is threaded, and the bottom of the finial 19 is provided with an axially extending recess interiorly threaded to match the thread on the actuator; whereby, with the lampshade frame 20 at its central eye 20a sleeving the actuator 28 where the latter projects above the cap 23, the finial may then be screwed down tight onto the actuator to lock the frame 20 to the general lamp structure, but, nevertheless, to permit the switch to be operated, and thereby to turn the lamp on or off, by manually imparting a slight tilting or rocking movement to the lampshade relative to the body 18 and consequently relative to the pedestal, regardless of the direction of application, inwardly radially of the lampshade, all around the circumference of the latter, of a tilt inducing pressure.

This rocking can be either a downward or upward one at the point on the lampshade engaged by the hand, and, as just stated, such point can be anywhere around the lampshade. Obviously, since the lampshade is of greatest diameter at its bottom, maximum mechanical advantage is obtained for up-pull on the actuator 28 when the rocking force is a lifting one at some point around the bottom of the lampshade; and this is fortuitous, since actual tests have demonstrated that the easiest and most naturally automatic way of attempting to effect the desired relative movement between the lamp parts is by upthrust of a finger against the bottom edge of the lampshade.

Whether the lampshade is rocked upwardly or downwardly, to turn the lamp on or off, there is an ideal lever action; and it will be noted that what in effect is provided is always a lever of considerable length with its fulcrum resident in some point around the top outer circumferentially

raised marginal portion 23b of the cap 23 of the body 18.

Referring to the form of the invention shown in Fig. 2, this shows the invention applied to a type of lamp wherein the socket for the bulb is upstanding atop the pedestal or other support, or upstanding relative to but offset from a main support, as the wall-plaque in the case of a so-called pin-up or wall lamp. Such a socket equipped lamp commonly embodies the familiar harp for carrying a lampshade support or frame above the bulb and at its own top having a threaded post on which a finial is to be screwed down to fasten said lampshade support to the harp. The form of the invention here elected to be shown embodies a pedestal and its base, generally marked 70. The pedestal suitably carries at its top a socket 71 for a bulb 72. Around the lower end of the socket, as usual, the bottom of a harp 73, by way of a central opening in such bottom, sleeves a neck 74 fixedly dependent from the socket; and in the familiar way a frame 75, for taking a lampshade 76, is secured to the top of the harp by a finial 77 screwed down onto a threaded post 76a fixed to the top of the harp.

The bottom of the neck 74 is flat and normally bears flat against the flat top of the pedestal. Suitably secured at its upper end within the neck is the actuator of the same kind of toggle switch as employed in Fig. 1; said switch and actuator here indicated at 80 and 81 respectively. The switch casing is suitably secured in the hollow interior of the upper end of the pedestal.

To control the lamp circuit, either to close or open the same, all that is required is to tilt the frame 75 up or down (and with it the harp and socket), a slight distance, by force applied at any point around the circumference of the frame 75, exactly as in Fig. 1. Here, however, the relative movement is between a lamp socket and a support therefor.

Still referring to Fig. 2, it will be noted that the pedestal is also shown as in two longitudinal pillar like sections, 84 and 85, above a bottom section 86 forming the base of the pedestal. Between each of these sections 84 and 85, in the same manner as just above explained in connection with the switch 80, is a like switch 87; and between the section 85 and the base 86, in the same manner as just above explained in connection with the switch 80, is a like switch 88.

Thus, in turning the lamp on or off, this may be accomplished, at will, by either rocking the socket relative to the pedestal as a whole, or rocking the upper pedestal section relative to the lower pedestal section 85, or by rocking the last-named section relative to the base 86 according, respectively, as the switch 88, only, of the three switches 80, 87 and 88 is present to act as such, or the switch 87 only is present to act as such, or the switch 88 only is present to act as such.

It will be understood that all structures illustrated herein are by way of illustration or exemplification only, and not in any way to be taken as delimitative of the invention. Variations and modifications are possible in divers ways, and parts of the improvements may be used without others. The scope of protection is to be taken solely from the appended claims, construed as broadly as is consistent with the prior art. In brief, all language herein is to be taken in an illustrative and not in a limiting sense.

Furthermore, while it will have been observed that in the forms of the invention illustratively shown herein the lampshade and the lampshade frame or support are shown as separate or sepa-

rable structures, it should be noted it is also standard practice now with some manufacturers to fabricate lampshades so that the shade itself is of such stiff material as to be self-sustaining in regard to shape, or to fabricate a lampshade wherein the frame or support, as a wire one of skeletal type, is permanently joined to or built into the lampshade; therefore, whenever herein a lampshade is mentioned, or a lampshade support or frame is mentioned, particularly in the claims, in either term there is included a lampshade of either of the two kinds just described.

I claim:

1. An electrically wired lamp comprising a main lamp structure, an electrically energizable illuminating means interposed in the circuit constituted by such wiring, a switch carried by said structure and also interposed in said circuit, said switch being inclusive of an operating mechanism having a projected universally rockable actuator, said mechanism operating in response to a rocking of said actuator to condition said switch to reverse the same as between circuit opening and circuit closing condition, a lampshade, and means for operatively connecting said lampshade and said actuator and operably associated with said main lamp structure to mount the lampshade tiltably on the latter, said means being so arranged that a tilt of the lampshade at any point therearound manually casually encountered correspondingly rocks said actuator.

2. A lamp as in claim 1, said switch being of a type such that when said actuator is rocked the switch is thrown to circuit closing or circuit opening condition dependent on whether the switch was previously in circuit opening or in circuit closing condition.

3. A lamp as in claim 1, said switch being of a type such that when said actuator is rocked the switch is thrown to circuit closing or circuit opening condition dependent on whether the switch was previously in circuit opening or in circuit closing condition, and said switch incorporating a resilient means for restoring the actuator to a normal direction of projection from the remainder of the switch following any rocking of the actuator to throw the switch to circuit opening or circuit closing condition.

4. A lamp as in claim 1, said switch being of a type such that when said actuator is rocked the switch is thrown to circuit closing or circuit opening condition dependent on whether the switch was previously in circuit opening or in circuit closing condition, there being means partially carried by the lampshade and partially carried by said lamp structure for affording a leverage contributing agent in regard to any tilt-imparting thrust on the lampshade applied at a point outwardly displaced from said actuator in any direction away from the latter.

DAVID TROMPETER.
